ABSTRACT OF THE DISCLOSURE

In an isomerization zone, C₈ aromatics are converted into xylene isomers and naphthalenes. Conventional isomerization techniques are used to produce the xylenes and naphthalenes, and conventional fractional crystallization techniques are then used to separate paraxylene from other isomers of xylenes. The distinguishing feature of my invention is the separation of the xylenes from the naphthalenes before crystallization and then recycling the naphthalenes to the isomerization zone.

BACKGROUND OF THE INVENTION

According to well known practice, a feed rich in C₈ aromatics and hydrogen is first passed through an isomerization zone maintained at suitable isomerization conditions and containing a suitable hydrogenation-dehydrogenation catalyst. Typical conditions and catalysts are illustrated in U.S. Pat. No. 2,976,332 and No. 3,180,839. In the isomerization zone, C₈-rich aromatics are converted to a mix of xylene isomers and naphthalenes, and then the mix is withdrawn from the isomerization zone.

This mix could be fed directly into a fractional crystallization unit where the different isomers of xylenes would be separated from each other using conventional techniques and standard refrigeration equipment. If this is done, however, the load on the refrigeration equipment would be high because of the presence of naphthalenes in the mix. The xylenes could be first separated from the naphthalenes and then fed to the fractional crystallization unit. If this is done the load on the refrigeration equipment is reduced, but yields of paraxylene, the most valuable isomer product, are also reduced.

DESCRIPTION OF THE INVENTION

I have invented a process for increasing the yield of paraxylene from a mixture of xylene isomers without placing an undue burden on the refrigeration equipment normally used in separating the paraxylene from other xylene isomers. According to my process, the naphthalenes are first separated from the xylenes and light byproducts and then recycled directly to the isomerization zone. When this is done, the yield of paraxylene will range between about 74–76 lbs./100 lbs. of xylene feed, as contrasted to a yield of 71 lbs. of paraxylene/100 lbs. of xylene feed when naphthalenes are separated from the xylenes but not recycled to the isomerization zone.

Separation of the light byproducts, naphthalenes and xylenes may be achieved by fractional distillation, with the naphthalene fraction boiling between the range of about 235 and about 265° F. Paraxylene recovery is achieved by conventional fractional crystallization. Any unseparated xylenes are recycled to the isomerization zone.

2**DESCRIPTION OF A PREFERRED EMBODIMENT**

The figure, which is a schematic flow diagram illustrating my process, shows C₈ aromatics from source 10 being mixed with hydrogen from source 12 and then fed via line 14 to isomerization zone 16. The effluent from isomerization zone 16, which is a mixture of light byproducts, naphthalenes and C₈ aromatics, flows via line 18 into stabilizing tower 20. The naphthalene-rich fraction boiling between 235–265° F. is drawn off through line 22 and recycled via this line and line 14 to zone 16. This maintains the optimum or near optimum equilibrium concentration of naphthalene in zone 16, so that most of the C₈ aromatics entering zone 16 are converted to xylenes. Optimum naphthalene concentration is dependent on pressure, temperature, and catalyst in zone 16, and will vary as these parameters vary.

Light byproducts boiling below 231° F. flow via line 23 out of the top of tower 20, and mixed xylenes flow via line 24 into xylene recovery tower 26. C₉ and higher hydrocarbons flow via line 28 from the bottom of tower 26, and the mixed xylenes escape from the top of tower 26 and flow via line 30 into conventional fractional crystallization zone 32. In crystallization zone 32, paraxylene is preferentially recovered and drawn off via line 35. Unseparated xylenes flow from zone 32 via line 36 and line 14 into isomerization zone 16.

I claim:

1. In a process for producing paraxylene wherein a feed rich in C₈ aromatics and hydrogen are passed through an isomerization zone maintained at suitable isomerization conditions and containing a suitable hydrogenation-dehydrogenation catalyst, whereby a substantially equilibrated mix of xylenes and naphthalenes form in said zone, and then said mix of xylenes and naphthalenes are withdrawn from the isomerization zone and the xylenes are passed through a fractional crystallization zone to separate paraxylene from other isomers of xylenes, the improvement comprising:
  - 40 separating the naphthalenes from the xylenes before said xylenes are passed into the fractional crystallization zone and recycling said naphthalenes to the isomerization zone.
  - 45 2. The process defined by claim 1 wherein separation of the xylene and naphthalenes is achieved by fractional distillation, with the naphthalene fraction boiling between about 235 and about 265° F.
  - 45 3. The process defined in claim 1 wherein unseparated xylenes are withdrawn from the fractional crystallization zone and recycled to the isomerization zone.
